TABLE FOR RUG SEWING MACHINES

Clyde S. Everett and James H. Ellis, Salem, Oreg.,
assignors to California Cotton Mills Company,
Oakland, Calif., a corporation of California

Application February 16, 1949, Serial No. 76,782

13 Claims. (Cl. 112—2)

1

This invention relates to rug manufacturing machinery, and more particularly, to a table for carrying a rug while the same is being sewed.

The conventional braided rug is usually made to a generally elliptical shape or to a rectangular shape, having at each end a semi-circular portion. Such rugs are constructed from a strip of material which generally comprises several strands of woven wool, flax or cotton braided together to form a relatively flat, elongated band. One such strip may be made from many braided strips joined together at their ends to form one continuous strip.

In manufacturing a braided rug such a strip is generally laid flat upon any convenient surface and turned back upon itself to form a return bend and then positioned so that two adjacent parallel strips are formed. These parallel strips are then stitched together along their common edge and the strip is then turned back around the connected strips to form another return bend and positioned so that three adjacent parallel strips are formed. This last strip is also sewed to the strips that already have been formed, and so on. This procedure results in the strip being formed to a substantially spiral shape, but deviating from a spiral in that the strip is continuously moving outwardly, not from a point, but from a line. However, the term "substantially spiral" will be used hereinafter to denote such a shape as described above.

Such sewing of strips to form a rug is best done on a sewing machine, but as the size of the rug becomes greater, the difficulty attending the process increases. The manual manipulation of the rug through the sewing machine normally becomes so difficult that greater speed may be effected by discarding the use of the sewing machine and finishing the rug by hand. If the use of the machine is continued it becomes necessary for the sewer to enlist the aid of several helpers to guide the rug through the machine.

One of the objects of this invention is the provision of a table for supporting a braided rug while it is being sewed, and which table will allow the sewing machine operator to sew the strips together in the form of a rug of predetermined shape without attention by such an operator to said table.

Another object of the invention is the provision of a table which will support a rug for rotation and at the same time, permit the continuous sewing of the rug around its periphery.

Another object of the invention is the provision of means to facilitate the handling of the rug as

2

its size progressively increases with the same ease and accuracy as when the rug is relatively small, and which handling is done without the necessity for enlisting the help of several persons as heretofore, and without stopping the machine.

An additional object is the provision of improved means to facilitate the accurate sewing of a braided rug without slowing down the process as the size of the rug increases.

Still another object of the invention is the provision of a table which may be readily adjusted to suit rugs of various sizes and which will permit the sewing of rugs regardless of the size of the same.

Yet another object of the invention is the provision of a table which will support a rug while the same is being sewed without requiring the attention of operators other than the sewer.

Other objects and advantages will be apparent from the specification and drawings.

Fig. 1 is a top plan view of a rug making machine showing the table as used in conjunction with a sewing machine, and showing only one table extension in place for clarity.

Fig. 2 is an end elevational view of the structure shown in Fig. 1.

Fig. 15 is a side elevational view of the structure shown in Fig. 13.

Fig. 16 is an enlarged cross-sectional view through the table top showing the means for securing the layers of the table together.

Sewing machine table

As best seen in Fig. 1, the invention comprises, in part, a conventional rug sewing machine 1 mounted on a table 2 having supports 3 attached to the floor. The table 2 is generally rectangular, but has attached thereto an elongated extension 4 disposed longitudinally in the direction of feeding through the sewing machine. A chair 5 on which the sewing machine operator may be seated is indicated in Fig. 1. The table for supporting the rug is generally designated 6.

On the side of the sewing machine opposite from the operator is a feeding device generally designated 8, which device is adapted to pull the rug through the machine in a direction away from the operator as the sewing proceeds.

As best seen in Figs. 5 and 6, the feeding device 8 comprises a standard 9 which may be attached to the table 2 by means of bolts 10 and nuts 11. Rigidly secured to the top of the standard 9 is a horizontally disposed cylindrical housing 12, through which extends a hollow shaft 13. The shaft 13 is rotatably secured to the inside wall of housing 12 by means of bearings 14. A collar 15 is provided adjacent one end of the housing 12 and is removably secured to one end of the hollow shaft 13 by means of set screw 16 (Fig. 6).

At the end of the housing 12 opposite the collar 15 is a collar 17 similar to collar 15, but having attached thereto an arm 18 which may be actuated in a manner to be described. The collar 16 is secured to the hollow shaft 13 by means of set screw 19.

The housing 12 and the hollow shaft 13 are positioned so that their axes are perpendicular to the direction of feed of the sewing machine and the standard 9 is at the end of the shaft 13 remote from the rug table 6.

Rigidly secured to the end of the hollow shaft 13 which is nearer the rug table 6 is a gear housing 21 in which is rotatably supported a gear 22. Another hollow shaft 23 is rigidly secured to gear housing 21 and carries at its free end a housing 24 to which is rotatably secured a roller 25.

The roller 25 is driven by electric motor 28 (Fig. 2) which may be secured to the under side of table 2. Pulleys 29, 30 mounted on the shaft of electric motor 28 drive belts 31, 32 respectively. Belt 31 is adapted to drive the sewing machine 2 by means of pulley 33 on the sewing machine shaft and belt 32 drives a pulley 34 on the end of shaft 35 which shaft is rotatably mounted within hollow shaft 13 by means of bearings 36 (Figs. 5, 6).

Integrally secured to shaft 35 adjacent its end remote from pulley 34 is a worm 37 which drives the gear 22 hereinbefore referred to (Fig. 5).

The gear 22, in turn, drives shaft 38 which is rotatably secured within hollow shaft 23 by means of bearings 39. The shaft 38 carries at its other end a bevel gear 40 which coacts with another bevel gear 41 at right angles to gear 40.

Bevel gear 41 is keyed to shaft 42, which shaft is rotatably mounted in housing 24 by means of bearings 43. The roller 25 is secured to shaft 42 by means of set screw 44, and has on its periphery a rubber covering 45 which provides the required friction to pull the rug through the sewing machine.

Thus, it is seen that the torque applied to pulley 34 by belt 32 drives the shaft 35 which is within the horizontal hollow shaft 13. Torque is transferred from shaft 35 to shaft 38 through worm and gear 37 and 22 respectively, and bevel gears 40, 41 transfer the torque to roller 25.

Hollow shaft 23 is made somewhat longer than the standard 9 so that the shaft is inclined to the horizontal when roller 25 rests upon the table 2 (Fig. 4). Although the roller 25 will normally rest on the table 2 or on a rug if one is being stitched, the roller may be removed from the table 2 by swinging the arm 18 upwardly. This is possible because the shaft 13 is rotatably supported within housing 12.

To permit the roller 25 to be forced downwardly upon a rug in order to provide the required traction a connecting rod 47 may be connected at one end to the free end of arm 18 and at the other end to a pedal 48, which pedal may be actuated by the foot of the operator. The roller 25 may be forced downwardly upon the rug by means of a spring, if desired, in which case the pedal may be used to release the roller from the rug.

Rug table support

The rug table, generally designated 6, is adapted to be supported on a vertical spindle 55 (Fig. 3), which spindle is rotatably secured to one end of an elongated, horizontally disposed support arm 56 by means of bearings 61 carried by arm 56 (Figs. 2, 3). This support arm 56 is pivotally connected at its other end by means of pin 57 to one end of another support arm 58 (Fig. 2). The support arm 58 is rotatably secured to a vertical pivot post 59 at its end remote from pin 57. The pivot post 59 is secured at right angles to a horizontally disposed flat base plate 60, which plate is secured to the floor by means of bolts 61.

Thus, it is seen that the spindle 55 on which the table 6 is secured may readily be positioned at any desired distance from the pivot post 59 up to the combined lengths of support arms 56, 58, and may be readily rotated, as desired, around the end of support arm 56 to which it is secured.

Rigidly secured to the under side of the rug table 6 is a track 63 which is formed to such a shape that it is parallel to the periphery of table 6 top and is spaced inwardly and downwardly therefrom. This track 63 may be in the form of a continuous vertically disposed flat bar which may be secured along its upper edge to the table 6 at spaced points therearound by means of brackets 64. The exact means for attaching the brackets 64 to the table will be described subsequently in detail in connection with the description of the rug table.

Coacting with the track 63 are three horizontally disposed coplanar guide rollers 66, 67, 68 (Figs. 7, 8, 9). Rollers 66 and 67 are positioned in side by side relationship on the side of the track 63 which is nearer the sewing machine (Fig. 1) and guide roller 68 is positioned on the opposite side of the track so that its center is on a line which perpendicularly bisects a line between the centers of rollers 66, 67 (Fig. 7).

To support the guide rollers 66, 67, 68 so that they may coact with track 63, a pair of spaced supports 69 are provided having a flat horizontally disposed cross member 70 connecting said supports at their upper ends. The rollers 66, 67 are rotatably secured by means of pins 71 to the bosses 72 which, in turn, are rigidly secured to cross member 70.

An upwardly opening channel member 73 is secured to the lower side of cross member 70 transversely of the same to form a box-like way in which an elongated square bar 74 is slidably secured. The end of bar 74 adjacent the rollers 66, 67 is formed to a circular cross-section to receive a helical compression spring 75 and the end of bar 74 is threaded for a nut 76 which permits adjustment of the compression in spring 75. The end of spring 75 (Figs. 7, 8) opposite the nut 76 bears against the end of channel member 73.

The roller 68 hereinbefore described, is rotatably secured to a pin 77 which, in turn, is secured to a boss 78 on bar 74. Thus, it is seen that the spring 75 urges the roller 68 towards rollers 66, 67 and when the track 63 is disposed between the rollers, the contact of all rollers with the track 63 is insured at all times.

For the purpose of moving the table 6 towards and away from the sewing machine 1 as desired, the supports 69 are secured to a pair of horizontally spaced parallel rails 81. Racks 82 are rigidly secured along the upper side of rails 81 by means of bolts 83 and coact with pinion gears 84. Drive shaft 85 disposed transversely of the rails 81 is journaled in bearings 86 and carries the pinions 84 for imparting a longitudinal motion to racks 82 upon rotation of shaft 85. The bearings 86 are supported on a transverse support member 87 positioned under the rails. This support member also serves to carry rollers 88 on which the rails 81 may roll. A support member 89 parallel to member 87 and spaced therefrom serves to carry similar rollers 90. A handwheel 91 is provided on the end of the shaft 85 which is closest to the sewing machine operator so that the table 6 may be moved by the operator with respect to the sewing machine, as desired.

Rug table top

As explained above, the rug table top is supported on a vertical spindle 55 for rotation with said spindle around the free end of upper support arm 56. This spindle is securely connected to the table top base 100 at right angles thereto by means of a sleeve 101 (Fig. 3) to which the spindle 55 is keyed by means of key 102. As hereinbefore explained, the table may be elliptical in shape or any other shape best calculated to support the type of rug to be made. Whatever the exact shape employed, the table top is braced by braces 103 which may be secured adjacent the periphery of the table at spaced points therearound and extend convergently downward to the sleeve 101 to which they may be secured in any convenient manner. The under side of the table top base may be stiffened as required by angle iron bars 79, or the like.

In the drawings, the track 63 with which rollers 66, 67, 68 coact is shown secured to the braces 103 near its upper edge, but it may be secured directly to the under side of the table top base, if desired.

As shown in Figs. 10-15, the table top actually comprises a plurality of layers which may be supported on the table top base 100 in a manner which will now be described.

A lower intermediate table top layer 105 (Fig. 11) is provided with four extensible arms 106 which may be approximately as thick as the layer 105 so that the same may rest within the layer 105 when the same is laid flat on the table top base 100. These extension arms 106 and other extension arms subsequently to be described, may be hollow tubular members formed of sheet metal

or may simply be formed of wood. The layers comprising the table top may also be of wood, in which case plywood is preferable because of its relatively great strength. The lower intermediate layer 105 may comprise four separate segments as shown in Fig. 11, which segments are secured to the table top base 100 in their proper relationship in a manner to be described. As best seen in Fig. 13, the arms 106 are adapted to be moved radially outwardly of the layer 105. To prevent movement of these arms beyond a predetermined point, stops 104 comprising a short length of angle iron or other appropriate material, are secured to the arms 106 adjacent their inner ends so that upon movement of the arms outwardly, the stops 104 engage the shoulder portions 113 formed on the edges of the segments of layer 105.

Positioned above lower intermediate layer 105 is a center layer 114 which is identical with the table top base 100, and is secured with respect thereto in a manner to be described.

Positioned above the center layer 114 is an upper intermediate layer 107 (Fig. 12) which is similar in construction to the lower intermediate layer 105, but is divided into eight segments and is provided with eight extension arms 108 which arms are positioned intermediate the arms 106 in a direction circumferentially of the table top. The arms 108 are provided with stops 119 which are adapted to engage shoulders 117 when the arms are withdrawn.

Positioned above the upper intermediate layer 107 is a top layer 118 which is identical with center layer 114 and the table top base 100. The table top base 100 and the layers 105, 114, 107 and 118 are all secured together against lateral movement relative to each other by means of pins 115 which are positioned within holes 116 in the above mentioned layers. Each of the holes 116 in each layer is in registration with corresponding holes in the other layers so that when pins 115 are inserted in holes 116 the various layers of the table top are secured together relative to table top base 100.

The pins 115 are provided with an enlarged head 121 and the holes 116 in top layer 118 are counter-sunk as at 122 to receive said head so that the pins may be dropped into place without the necessity of screwing nuts or the like, on the pins 115.

When the extension arms 106 and 108 are extended outwardly, additional table segments 109, 110 may be placed thereon to increase the area of the table. Since the layer 107 is somewhat above the layer 105, blocks 111 and 112 are secured to table segments 109 and 110 respectively to compensate for the said difference in level.

As best seen in Fig. 3, the spindle 55 is provided with a hand wheel 125 threadedly secured to the spindle 55 adjacent the support arm 56. Upon rotating this hand wheel 113, the hub of which engages the lower end of sleeve 101, the table may be adjusted upwardly or downwardly. This adjustment becomes important when the rug overhangs the table so that the edge of the rug tends to drop below the working level of the sewing machine.

Operation

It can be seen from the foregoing description that a rug may be placed on the table 106 after the same has attained such a size that manual feeding through the sewing machine becomes difficult. The table top may be moved towards

the sewing machine by means of hand wheel 91 and the rug placed adjacent the sewing machine and under wheel 25. Sewing may then be commenced and the pedal 48 actuated by the foot of the sewing machine operator to permit wheel 25 to pull the rug through the machine. Inasmuch as the table 6 is "floating" on bearings 61 and pins 57 and pivot post 59, the rug table will rotate and move laterally as required to allow the rug to be fed through the sewing machine. It is pertinent to note that the track 63 is virtually a guide track or means, and should be parallel to the periphery of the table so that when a rug is centered on the table, the feeding through the sewing machine will be accomplished without any transverse pull on the rug.

It is apparent from the foregoing that as the rug becomes larger the operator may move the table away from the machine by means of hand wheel 91.

A rug resting on the table top will normally be heavy enough to prevent movement of the rug with respect to the table top, but if required, any suitable weights may be placed on the rug to prevent movement of the same with respect to the table top.

We claim:

1. A table for use with a sewing machine for supporting the coil of a braided rug during the sewing of a strip of fabric together by such machine to form said coil, means for supporting said table adjacent such machine and at about the level of the sewing point thereon for rotation of said table about a vertical axis and for bodily movement of said table toward and away from said machine, a carriage below said table supported for movement toward and away from said machine, an endless track stationarily connected with said table for movement therewith, guide elements secured on said carriage movable therewith, said guide elements being connected with said guide track for linear movement of said track in a path past said elements and in engagement with said elements upon revolution of said table whereby the periphery of said table will follow a path substantially corresponding with and parallel to that defined by said track during said rotation, and means for moving said carriage toward and away from said machine.

2. A table for use with a sewing machine for supporting the coil of a braided rug during the sewing of a strip of fabric together by such machine to form said coil, means for supporting said table adjacent such machine and at about the level of the sewing point thereon for rotation of said table about a vertical axis and for bodily movement of said table toward and away from said machine, the means supporting said table for rotation and for said bodily movement including a pair of arms pivotally connected together at one of their ends for horizontal swinging of the other end of one of said arms and the other arm of said pair being pivoted for horizontal swinging of the connected ends of said arms, a vertical pivot on said other end of one of said arms supporting said table for rotation thereon, guide means connected with said table for restricting its periphery to movement through a predetermined point upon rotation of said table.

3. A table for use alongside a sewing machine for supporting the coil of a braided rug during sewing of a braided strip of fabric together by such machine to form said coil, an arm, a pivot

horizontally spaced from the center of said table and supporting one end of said arm for swinging of the opposite end in a horizontal plane, means supporting said table horizontally on said opposite end of said arm for rotation of said table in a horizontal plane relative to said arm, interconnected guide members respectively secured to said table for rotation therewith and to a base separate from said table for guiding the periphery of said table through a predetermined point during said rotation of the latter, means supporting said base for movement toward and away from said machine for causing movement of said point toward and away from said machine as desired.

4. A table for use alongside a sewing machine for supporting the coil of a braided rug during sewing of a braided strip of fabric together by such machine to form said coil, an arm, a pivot horizontally spaced from the center of said table and supporting one end of said arm for swinging of the opposite end in a horizontal plane, means supporting said table horizontally on said opposite end of said arm for rotation of said table in a horizontal plane relative to said arm, interconnected guide members respectively secured to said table for rotation therewith and to a base separate from said table for guiding the periphery of said table through a predetermined point during said rotation of the latter, means supporting said base for movement toward and away from said machine for causing movement of said point toward and away from said machine as desired, a second arm, said pivot being carried on one end of said second arm with the opposite end of said second arm supported for swinging of said one end thereof, including said pivot, in a horizontal plane, and means for so supporting said opposite end of said second arm.

5. A table for use alongside a sewing machine for supporting the coil of a braided rug during sewing of a braided strip of fabric together by such machine to form said coil, an arm, a pivot horizontally spaced from the center of said table and supporting one end of said arm for swinging of the opposite end in a horizontal plane, means supporting said table horizontally on said opposite end of said arm for rotation of said table in a horizontal plane relative to said arm, interconnected guide members respectively secured to said table for rotation therewith and to a base separate from said table for guiding the periphery of said table through a predetermined point during said rotation of the latter, means supporting said base for movement toward and away from said machine for causing movement of said point toward and away from said machine as desired, the guide means secured on said table being a horizontally disposed endless track in a plane parallel with said table and extending parallel with the periphery of said table, and the guide means on said base being elements in engagement with opposite sides of said track and between which said track is movable longitudinally thereof upon rotation of said table.

6. A table for use alongside a sewing machine for supporting the coil of a braided rug during sewing of a braided strip of fabric together by such machine to form said coil, an arm, a pivot horizontally spaced from the center of said table and supporting one end of said arm for swinging of the opposite end in a horizontal plane, means supporting said table horizontally on said opposite end of said arm for rotation of said table in a horizontal plane relative to said arm,

interconnected guide members respectively secured to said table for rotation therewith and to a base separate from said table for guiding the periphery of said table through a predetermined point during said rotation of the latter, means supporting said base for movement toward and away from said machine for causing movement of said point toward and away from said machine as desired, the guide means secured on said table being a horizontally disposed endless track in a plane parallel with said table and extending parallel with the periphery of said table, and the guide means on said base being rollers in engagement with opposite sides of said track and between which said track is movable longitudinally thereof upon rotation of said table, means connected with one of said rollers at one side of said track for yieldably urging said roller into engagement with said track at all times.

7. A table for use alongside a sewing machine for supporting the coil of a braided rug during the sewing of a braided strip of fabric together by such machine to form said coil, means for supporting said table for rotation thereof about a vertical axis and for bodily movement of said table toward and away from said machine, a horizontal endless guide track below said table rigid therewith and extending parallel with the peripheral edge of said table, a fixed base below said track, means on said base engaging said track at a point therealong nearest said machine for linear movement of said track therewith and in engagement therewith during rotation of said table whereby the edge of said table adjacent said machine will be restricted to movement through a predetermined point when the table is rotated, a carriage supporting said means for movement to different distances toward and away from said machine whereby said predetermined point may be varied.

8. A table for use alongside a sewing machine for supporting the coil of a braided rug during the sewing of a braided strip of fabric together by such machine to form said coil, means for supporting said table for rotation thereof about a vertical axis and for bodily movement of said table toward and away from said machine, a horizontal endless guide track below said table rigid therewith and extending parallel with the peripheral edge of said table, a fixed base below said track, means on said base engaging said track at a point therealong nearest said machine for linear movement of said track therewith and in engagement therewith during rotation of said table whereby the edge of said table adjacent said machine will be restricted to movement through a predetermined point when the table is rotated, a carriage supporting said means for movement to different distances toward and away from said machine whereby said predetermined point may be varied, and means accessible to an operator at such machine and alongside said table for causing said movement of said carriage.

9. A table for use alongside a sewing machine for supporting the coil of a braided rug during the sewing of a braided strip of fabric together by such machine to form said coil, means for supporting said table for rotation thereof about a vertical axis and for bodily movement of said table toward and away from said machine, a horizontal endless guide track below said table rigid therewith and extending parallel with the peripheral edge of said table, a fixed base below said track, means on said base engaging said track at a point therealong nearest said machine for

linear movement of said track therewith and in engagement therewith during rotation of said table whereby the edge of said table adjacent said machine will be restricted to movement through a predetermined point when the table is rotated, a carriage supporting said means for movement to different distances toward and away from said machine whereby said predetermined point may be varied, said table being of generally elliptical shape.

10. A table top for use alongside a sewing machine for supporting the coil of a braided rug during the sewing of a strip of fabric together to form said coil, means for supporting said table top adjacent said machine for rotation and for bodily movement toward and away from said machine, a plurality of arms below said table top for radial extension to various points outwardly of the periphery of said table top for supporting flat sections therein coplanar with said table top whereby the area of said table top may be extended, means securing said arms to said table top for radial movement relative thereto to said points, said arms being arranged successively in groups in different horizontal planes below the plane of said table top, the arms of the group next to said table top being extensible independently of the group therebelow and the arms of said last mentioned group being extensible to the same distance from said table as the arms of the group nearest said table.

11. A table top for use alongside a sewing machine for supporting the coil of a braided rug during the sewing of a strip of fabric together to form said coil, means for supporting said table top adjacent said machine for rotation and for bodily movement toward and away from said machine, a plurality of arms below said table top for radial extension to various points outwardly of the periphery of said table top for supporting flat sections therein coplanar with said table top whereby the area of said table top may be extended, means securing said arms to said table top for radial movement relative thereto to said points, and sections for securing to said arms when the latter are extended, said sections being elongated and linearly conforming to the outline of said table, said table being generally elliptical in shape, a table top base below said table top and below the lowermost group of arms conforming in shape to said table top and parallel therewith.

12. In a sewing machine for sewing a braided strip of fabric together in a planar coil to form a braided rug, a horizontal table adjacent said machine for supporting said coil during said sewing, a base below said table including a track extending toward said table, a carriage supported on said track for movement toward and away from said machine, an endless guide track below said table rigid therewith and extending parallel with the peripheral edge of said table, means supporting said table for rotation in the plane thereof and for bodily movement in any direction in said plane, members on said carriage engaging said guide track at the point thereon nearest said machine for restricting linear movement of said guide track to between said members.

13. In a sewing machine for sewing a braided strip of fabric together in a planar coil to form a braided rug, a horizontal table adjacent said machine for supporting said coil during said sewing, a base below said table including a track extending toward said table, a carriage supported on said track for movement toward and away from

said machine, an endless guide track below said table rigid therewith and extending parallel with the peripheral edge of said table, means supporting said table for rotation in the plane thereof and for bodily movement in any direction in said plane, rollers on said carriage rotatable about vertical axes engaging opposite lateral sides of said guide track at the point thereon that is adjacent said machine for restricting the linear movement of said guide track to between said rollers.

CLYDE S. EVERETT.
JAMES H. ELLIS.
